UNITED STATES PATENT OFFICE.

STUART FLEMING, OF OWEN SOUND, ONTARIO, CANADA.

ZINC-PLATE CYLINDER FOR OFFSET LITHOGRAPHING PRESSES.

Application filed November 29, 1920. Serial No. 427,103.

To all whom it may concern:

Be it known that I, STUART FLEMING, a subject of the King of Great Britain, of the city of Owen Sound, in the county of Grey, in the Province of Ontario, Canada, have invented certain new and useful Improvements in Zinc-Plate Cylinders for Offset Lithographing Presses, of which the following is the specification.

10 My invention relates to improvements in zinc plate cylinders for offset lithographing presses and the object of the invention is to devise a cylinder having a plurality of segments on which are mounted independent zinc plates. A further object is to provide means for readily attaching the zinc plates to the segments of the cylinder and a further object is to construct a cylinder in which a plurality of separate and distinct lithographing jobs can be run off at the same time instead of having to do these jobs separately. A still further object is to construct a cylinder which will permit of the use of rolls of paper instead of sheets which have hitherto been employed with offset lithographing presses.

My invention consists of a zinc plate cylinder constructed and arranged substantially as hereinafter more particularly described and illustrated in the accompanying drawing in which:

Fig. 1 represents a side elevation of a portion of an offset lithographing press showing my cylinder applied thereto.

Fig. 2 is a side view of a cylinder constructed according to my invention showing the upper portion in elevation and the lower portion in section.

Fig. 3 is an end view of one of my cylinders, and

Fig. 4 is a detail in plan of one of my zinc plates showing the means of attachment to the cylinder segments.

Like characters of reference indicate corresponding parts in the different views:

1 is the frame of the press. 2 is a paper roll. 3 is the paper adapted to be wound off the roll 2 over the rollers 4 and 5 and between the feed roller 6 and the printing roller 7. 8 is my zinc plate cylinder suitably mounted in bearings 9 in the frame 1.

10 are the ends of the cylinder provided with the bosses 11 and shafts 12 by means of which the cylinder is mounted in the bearings 9 of the frame 1. 13 are the cylin-

der segments suitably secured to the ends 10 of the cylinder by the screws 14 threaded into longitudinal holes 15 in the ends of such cylinder segments. The segments 13 are mortised into the ends 10 as shown at 16, 60 (Fig. 2). 17 is a cylindrical member joining the bosses 11 together and formed integrally therewith, the cylinder ends 10 being mounted on such bosses 11 and being preferably circular in shape. 65

The interior of one end of each segment 13 is bevelled off as is shown at 18 (Fig. 3), the other end of each segment being substantially rectangular and the outside corner rounded off. 70

19 is an annular web inserted between the member 17 and the cylinder segments 13 and designed to give strength to the centre of the cylinder segments. 20 are the zinc plates carrying the lithographing matter, each of said plates being hinged at one end to a plate 21 as is shown at 22 (Fig. 4). The plate 21 is preferably constructed of light gauge steel and has a longitudinal slot 23 therein to permit the plate to extend on each side of the annular web 19. 24 are holes in the bottom edge of the plate 21 through which the cap screws 30 pass when the plate 21 is firmly secured between a flattened surface on the shaft 29 and the binding plates 31, by tightening the heads of the cap screws 30 which screw into the shaft 29 against the binding plates 31. 80

25 are suitably spaced sockets at the upper edge of the plate 21 adapted to be inserted 90 between suitably spaced opposed sockets 26 formed on the lower edge of the zinc plate 20. 27 is a rod extending through the aforesaid sockets for hinging the plates 20 and 21 together. 95

28 are ratchet wheels mounted on the shafts 29 and extending longitudinally through the cylinder between the member 17 and the cylinder segments 13. 30 are cap screws adapted to be threaded into the 100 shafts 29 and to carry the binding plates 31, said shafts 29 being freely mounted in the ends 10 of the cylinder.

32 are pawls pivotally connected to the ends 10 and adapted to engage the teeth 105 of the ratchet wheels 28 as is shown in Fig. 3. 33 are squared ends on the shafts 29 to which a box-spanner can be applied for the purpose of turning such shafts. 34 are shafts freely mounted in the ends 10 and ex- 110

tending longitudinally through the cylinder between the segments 13 and the member 17, the ends of said shaft projecting out from the cylinder ends 10. Each of the shafts 34 has an outwardly extending plate 35 formed thereon or suitably secured thereto. 36 are arms, each provided with the hollow boss 37 adapted to extend over the end of the corresponding shaft 34 and to be secured thereto by the pin 38. The free end of each arm 36 is provided with a threaded screw 39 having the squared end 40 and the lock nut 41.

On reference to Fig. 3 of the drawings it will be seen that the cylinder segments 13 do not abut each other but are spaced apart a certain extent. This permits of the plates 20 and 21 being inserted therebetween as will hereinafter appear.

20 The zinc plates 20 are applied to the cylinder segments 13 as follows:

The upper end of the zinc plate 42 is bent over into the position shown in Fig. 3 and inserted between the tapered end 18 of the cylinder segment 13 and the plate 35 on the shaft 34.

By unscrewing the lock nut 41 the threaded screw 39 can be tightened up by applying a box-spanner thereto. As the inner end of the screw 39 engages the boss 11 of the member 17, by turning the bolt 39 the arm 36 will be forced away from such boss. When this occurs the shaft 34 is turned and with it the plate 35 which is pressed firmly against the turned over end 42 of the zinc plate 20. Thus the end of the zinc plate is held firmly between the plate 35 and the tapered end 18 of the segment 13.

40 The upper edge of the plate 21, which plate is fastened to the shaft 29 as described above, extends through an opening between the cylinder segments 13. The sockets 26 on the lower edge of the plate 20 are inserted between the suitably spaced sockets 25 on the upper edge of the plate 21 as described above, and the rod 27 is inserted through the sockets, thus connecting 20 and 21.

45 The zinc plate now being firmly attached at both ends, the shaft 29 is turned by applying the box-spanner to the squared end 33 thereof. This draws the plate 21 taut and with it the zinc plate 20 so that such zinc plate is drawn down tightly onto the surface of the cylinder segments 13.

50 All the zinc plates are applied to the different segments in exactly the same manner as described above and consequently it will be seen that such construction will enable any one of the zinc plates to be changed 55 without interfering with the other plates.

55 From the above description it will be seen that I have devised a zinc plate cylinder to which different segments can be applied independently, said segments containing different lithographing matter thus enabling

the operator to do a plurality of jobs at the same time.

Hitherto in offset printing presses the zinc plates only extended for a certain portion of the circumference of the cylinder and the remaining part of the circumference was wasted. In my device I make use of a plurality of segments suitably spaced apart giving a printing surface of the entire circumference of the cylinder, except for a small space between each segment which corresponds with and represents the bottom and top margin of the adjacent forms being lithographed.

Hitherto it has been the practice to use the paper stock in sheets of the required size, and this is essential where only one segmental zinc plate is used on the cylinder. In my cylinder however where I use zinc plates for the entire circumference of the cylinder the paper stock may be used in rolls, thus effecting a considerable economy in paper as well as saving much time in handling the same.

What I claim as my invention is:

1. In a zinc plate cylinder for offset lithographing presses, the combination with the cylinder, of segmental zinc plates, the one end of each zinc plate being turned over inwardly and clamped in the cylinder, shafts freely mounted in the cylinder, plates hinged to the other ends of the zinc plates and secured to said shafts and means for turning the shafts for drawing the zinc plates taut against the cylinder.

2. In a zinc plate cylinder for offset lithographing presses, the combination with the cylinder, of segmental zinc plates, the one end of each zinc plate being turned over inwardly and clamped in the cylinder, shafts freely mounted in the cylinder, plates hinged to the other ends of the zinc plates and secured to said shafts, said shafts projecting beyond the ends of the cylinder, ratchet wheels on said ends of the shafts and pawls 110 engaging the teeth of said ratchet wheels, the ends of said shafts being squared.

3. In a zinc plate cylinder for offset lithographing presses, the combination with the cylinder, of segmental zinc plates, the one end of each zinc plate being turned over inwardly, longitudinal shafts freely mounted in the cylinder, said shafts carrying outwardly extending plates, the turned over end of the plate being clamped between the outwardly extending plate of the shaft and the cylinder, means for tightening the outwardly extending plate on the shaft down onto the inwardly turned over end of the zinc plate, shafts freely mounted in the cylinder, plates hinged to the other ends of the zinc plates and secured to said shafts, said shafts projecting beyond the ends of the cylinder, ratchet wheels on said ends of the shafts and pawls engaging the teeth 120 of the shafts and pawls engaging the teeth 125

of said ratchet wheels, the ends of said shafts being squared.

4. In a zinc plate cylinder for offset lithographing presses, the combination with the cylinder, of segmental zinc plates, the one end of each zinc plate being turned over inwardly, longitudinal shafts freely mounted in the cylinder, said shafts carrying outwardly extending plates, the turned over end of the plate being clamped between the outwardly extending plate of the shaft and the cylinder, arms suitably secured to the ends of each longitudinally extending shaft, a bolt threaded into the free end of each 10 of the arms, a squared outer end on each bolt, a locking nut on each bolt, shafts freely mounted in the cylinder, plates hinged to the other ends of the zinc plates and secured to said shafts, said shafts projecting 15 beyond the ends of the cylinder, ratchet wheels on said ends of the shafts and pawls engaging the teeth of said ratchet wheels, the ends of said shafts being squared.
5. In a zinc plate cylinder for offset lithographing presses, a cylinder comprising a central cylindrical member having outwardly extending bosses formed thereon, cylinder ends keyed to the said bosses, cylinder segments suitably secured to the said cylinder ends and segmental zinc plates detachably mounted on the said cylinder segments, one end of each segmental zinc plate secured to the corresponding end of the cylinder segment and the other end adjustably secured to the cylinder, longitudinal shafts freely mounted in the cylinder ends and extending between the inner cylindrical member and the cylinder segments, plates hinged to the zinc plates, bolts on the said 20 shafts, said hinged plates having suitably spaced holes corresponding with the spacing of the bolts on the shafts, said bolts inserted in said holes, securing plates having suitable holes, said bolts extending through 25 said holes in the securing plates and nuts threaded on the bolts and screwed down against the securing plates, means for revolving the shafts, the ends of the shafts projecting out from the cylinder ends, ratchet wheels mounted on the said ends, pawls pivotally connected to the cylinder ends engaging the teeth of the ratchet wheel the extremity of one end of each shaft being 30 squared.
- 35
- 40

spacing of the bolts on the shafts, said bolts inserted in said holes, securing plates having suitable holes, said bolts extending through said holes in the securing plates 45 and nuts threaded on the bolts and screwed down against the securing plates, means for revolving the shafts and means for retaining the shafts in any revolved position.

6. In a zinc plate cylinder for offset lithographing presses, a cylinder comprising a central cylindrical member having outwardly extending bosses formed thereon, cylinder ends keyed to the said bosses, cylinder segments suitably secured to the said cylinder ends and segmental zinc plates detachably mounted on the said cylinder segments, one end of each segmental zinc plate secured to the corresponding end of the cylinder segment and the other end adjustably secured to the cylinder, longitudinal shafts freely mounted in the cylinder ends and extending between the inner cylindrical member and the cylinder segments, plates hinged to the zinc plates, bolts on the said 50 shafts, said hinged plates having suitably spaced holes corresponding with the spacing of the bolts on the shafts, said bolts inserted in said holes, securing plates having suitable holes, said bolts extending through 55 said holes in the securing plates and nuts threaded on the bolts and screwed down against the securing plates, means for revolving the shafts, the ends of the shafts projecting 60 from the cylinder ends, ratchet wheels mounted on the said ends, pawls pivotally connected to the cylinder ends engaging the teeth of the ratchet wheel the extremity of one end of each shaft being 65 squared.
